UNITED STATES PATENT OFFICE.

JULIUS H. GARSON, OF DENVER, COLORADO.

PIPE-WRENCH.

SPECIFICATION forming part of Letters Patent No. 632,257, dated September 5, 1899.

Application filed March 22, 1898. Serial No. 674,759. (No model.)

To all whom it may concern:

Be it known that I, JULIUS H. GARSON, a citizen of the United States, residing at Denver, in the county of Arapahoe and State of Colorado, have invented certain new and useful Improvements in Pipe-Wrenches; and I do hereby declare the following to be a full, clear, and exact description of the invention, such as will enable others skilled in the art to which it appertains to make and use the same.

The object of my invention is to provide a pipe-wrench containing cogged wheels which may be clamped upon a pipe by means of a rod in the handle of said wrench, which acts as the thumb-screw does on the ordinary wrenches now in common use. I attain these objects by the mechanism illustrated in the accompanying drawings, in which—

Figure 1 is a sectional view of the pipe-wrench, showing the entire device. Fig. 2 is a view of a vertical section of the same. Fig. 3 is a view of die, socket, and wrench as stock. Fig. 4 is a view of a vertical section of the same as Fig. 3. Fig. 5 is an interior view of the lower section of the stock. Fig. 6 is a view of a cross-section of the die. Fig. 7 is a view of die, socket, and bushing.

Similar figures refer to similar parts throughout the several views.

30 In Plate 1, 5 is the outside shell or solid part of the wrench in which the mechanical parts are contained or to which they are attached.

5^a is a portion of the shell extending well upon the handle 6 to give additional strength 35 to the whole device.

5^d 5^d are rivet or screw holes in the shell 5 to receive rivets or screws to be used in fastening and holding the two equal parts of the wrench together.

40 6 is the handle of the wrench, containing a cavity to receive the rod 7, around which the handle 6 is intended to revolve. The rod 7 has a thread thereon, and the cavity in the handle 6 also has a thread to receive the rod

45 7, and the handle 6 is loose around the rod 7, but secured to the shell 5 by a shoulder or other suitable means at the lower end of the handle 6, so that by turning the handle 6 the rod 7 will be drawn into or extended out of 50 the handle 6, thereby contracting or expanding the space between the clamp-wheels 12, 13, 12, and 9.

T^a is a pin passing through the rod 7 and

the ends thereof secured to the lug 8 to prevent the rod 7 from turning while operating 55 with the thread in the handle 6.

8 is the lug fixed to the rod 7, containing a cavity in which the clamp-wheel 9 is pivoted. By revolving the handle 6 about the rod 7 the lug 8, together with the clamp-wheel 9, 60 may be adjusted to any desired distance relative to the other clamp-wheels 12, 13, and 12. Thus the wrench will clamp upon any ordinary-sized pipe.

9 is the clamp-wheel, contained partially 65 within the cavity in the lug 8. Said clamp-wheel 9 has a saw or other suitable edge in order that the pipe may be held firmly when the clamp-wheel 9, in connection with the clamp-wheels 12, 13, and 12, similarly constructed, is brought in contact with the pipe by means of the revolving handle 6, the thread therein, and the rod 7, with the thread thereon.

10 is a pivot upon which the clamp-wheel 9 75 operates. The pivot 10 passes through the clamp-wheel 9 and also through the lug 8 to its outer edges and flush with the same.

12, 13, and 12 are clamp-wheels in the forward end of the wrench, which act in conjunction with the clamp-wheel 9 in lug 8 upon the pipe when the wheel 9 is advanced against the pipe by means of the revolving handle 6, as before described. As the wheel 9 is advanced, the pipe is forced against the clamp-wheels 12, 13, and 12 and the pipe is then firmly fixed in position by being pressed between the clamp-wheels 9, 12, 13, and 12. 85

12 and 12 are the clamp-wheels upon which the ratchets or dogs 16 and 17 in the shell 5 90 of the wrench operate. These clamp-wheels 12 and 12 are pivoted directly in the shell 5 by means of pins 14 and 14 and are of the same construction as the clamp-wheel 9. They may be adjusted in the direction of 95 their movement by means of the ratchets or dogs 16 and 17.

13 is a loose clamp-wheel constructed and pivoted in a like manner as the clamp-wheels 12 and 12, but is not controlled by ratchets, 100 as they are. This clamp-wheel is placed between clamp-wheels 12 and 12, but not in contact therewith.

14 14 are screws or pivots used to secure the clamp-wheels 12, 13, and 12 in position 105 within the shell 5.

- 19 and 19 are the pins upon which the pawls 16 and 17 are pivoted to the shell 5.
- 20 20 are the springs which hold the pawls 16 and 17 in position.
- 5 21 21 are pins which keep the springs 20 20 bent or sprung.
- 22 is a plate used to cover the opening in shell 5. This plate is riveted to the shell 5 or solid part of the wrench by the rivets 5^a.
- 10 25 in Fig. 3 is the die in the casing 26 when all the clamp-wheels of the wrench are brought in contact with the same.
- 26 is the outer casing of the die 25, having a saw edge or cogs acting in the clamp-wheels 9, 12, 13, and 12.
- 15 26^a is the outer casing around the pipe-socket, as shown in Fig. 7.
- 26^c is the lug held in place in die 25 by screws 31.
- 20 27 is the bushing, with screw thereon, to act in conjunction with the thread in the pipe-socket 26^a.
- 28 is the set-screw to hold the bushing in place upon the pipe.
- 30 is the lug-plate to hold the die in place 25 in the socket of casing 26.
- 31 is the screw which holds the lug-plate 30 in the casing 26 to prevent the die 25 from falling out.
- Having thus fully explained my invention 30 in such a manner that those versed in the art to which it belongs may fully understand its operation, what I claim as my invention, and desire to secure by Letters Patent, is—
- The combination of the frame, a pipe- 35 wrench with a series of clamp-wheels, one or more, of which is pivoted to a lug that is attached to a rod that screws into a revolving handle; two of the said clamp-wheels of the series being regulated in the direction of their 40 movement, or fixed by double pawls which are attached or pivoted to the shell of the wrench; whereby the wrench is adjusted to fit various-sized pipes substantially as described.

JULIUS H. GARSON.
